ENGINE STARTING SYSTEM.

1,312,549.

Specification of Letters Patent. Patented Aug. 12, 1919.

Application filed May 25, 1915. Serial No. 30,399.

To all whom it may concern:

Be it known that we, CHARLES F. KETTERING and WILLIAM A. CHRYSST, citizens of the United States of America, residing at Dayton, county of Montgomery, and State of Ohio, have invented certain new and useful Improvements in Engine Starting Systems, of which the following is a full, clear, and exact description.

10 This invention relates to improvements in engine starting systems, and more particularly to that type of starting systems which are to be applied to the driving motors of self-propelled vehicles.

15 Among the objects of the present invention is to provide a starting system which includes a motor-generator, which may be operable as a four pole motor of high torque when used as a motor for starting the engine, and can then be converted into a two pole generator when the engine becomes self-actuating and tends to run the motor-generator as a generator to supply current for charging of storage batteries, or for supplying current for the ignition system, lighting system or other purposes.

20 It is another object of the present invention to provide a starting system, wherein the motor-generator may be operated as a four pole motor of high torque for actually starting the engine, and as a two pole motor for securing the initial operation of the electric machine, so as to facilitate the mechanical connecting up of the electric machine 25 with the engine for starting purposes.

25 Further objects and advantages of the present improvements will be apparent from the following description, reference being had to the accompanying drawings, wherein 30 a preferred embodiment of the present invention is clearly set forth.

In the drawings hereto annexed:

35 Figure 1 is a general diagram of the circuit connections employed in carrying out the invention.

40 Fig. 2 is a top plan view of the engine of a motor vehicle, showing the location and relation of the dynamo-electric machine used therewith.

45 Fig. 3 is a plan view of the dynamo-electric machine with parts of the casing and frame in section.

50 Fig. 4 is an end view of the same.

55 Fig. 5 is a sectional view of the dynamo-electric machine, showing the form and con-

struction of the field magnets and other parts.

Figs. 6 and 7 are detail views of portions of the field structure.

Fig. 8 is an enlarged sectional detail of 60 the gearing used with the machine.

Fig. 9 is an end view of the gears.

Fig. 10 is an enlarged side view of the commutator end of the machine.

Fig. 11 is an end view of the brush shift- 65 ing and controlling mechanism, and

Fig. 12 is a detail view of a cam for shifting the brushes.

In these drawings the well known appurtenances of a motor vehicle, such as are almost universally employed, and hence well known, are not illustrated except diagrammatically, the illustration being confined to the novel features of the invention, except in Fig. 2, which shows the general arrangement of parts mounted on a chassis 2. The dynamo-motor in this figure is designated by 3 and its gear connection with the engine by 4.

Referring now to Fig. 11, there is shown in section a camming rod 5 adapted to be 80 connected with and operated by a hand lever or foot pedal, which is not shown. On the rod 5 is a cam 6 shown in Fig. 12, which engages a lug 7 on a camming ring 8 mounted at the end of the dynamo-motor by means of 85 pins or screws 9 passing through curved slots 10 in the ring. According to the relative position of the cam 6, the ring 8 is shifted around the axial center of the machine, a spiral spring or springs 11 tending to rotate 90 it at all times in a direction opposite to that in which it is forced by the cam 6.

On studs 12, Fig. 10, fixed to the frame of the machine, a plurality of brushes, illustrated herein as four in number, 13, 14, 15, 95 and 16, are mounted, and by means of springs 17 are normally impelled toward the segments of a commutator 18. On other studs 19, are mounted two brushes 20, which are similarly impelled by springs toward 100 the commutator 42. As shown in the drawings, the brushes 20 bear upon diametrically opposite points of their commutator, while the brushes 13 to 16 are located at points 90° from each other and intermediate to the 105 brushes 20.

On the ring 8 are placed insulating studs or projections 21, which, according to the position of the ring, engage with brushes 20 or brushes 14 and 16, and while in such en- 110

- gagement lift one or the other set of brushes from the commutators. The brushes 14 and 16 have pins or studs 22 which are adapted to engage with similar pins 23 on brushes 13 and 15, so that when the former are lifted by the pins or studs 21 they turn the latter about their pivotal bearings and all four brushes are similarly shifted. Other means may be employed for raising the 10 brushes, if so desired. In the normal position of the parts above described, the cam 6 is in full operative engagement with the lug 7, and the ring 8 is maintained in the position in which the brushes 20 are in contact with and the brushes 13 to 16 are raised from their respective commutators, but in Fig. 11 the parts are shown as in the extreme opposite relations, with the brushes 20 raised and the others lowered.
- 20 The various gear connections are shown in Figs. 8 and 9, in which 24 represents the armature shaft of the dynamo-motor. This shaft carries near its end a pinion 25 and a clutching element, which comprises a disk 26 with notches of the form shown in Fig. 9. Concentric with the clutch disk is a gear wheel 27 and rollers or balls 28 are retained in the notches between closing plate 29 and the inner periphery of the gear wheel 27. A 30 projection 30 from the gear wheel 27 is connected with the timing gears in the engine.

Beneath the armature shaft and parallel therewith is a shaft or spindle 31 which carries a clutching element 32 similar in construction to that described above, and provided with a pinion 33. A gear wheel 34 concentric with and coöperating with the clutch element, carries a yoke or grooved extension 35, and the clutch and pinion are 35 loosely mounted on the shaft 31 and slidable thereon, so that in one position the pinion 33 will gear with the wheel 27 and the gear 34 with the pinion 25, but when moved to the right, see Fig. 8, it will be entirely out of 40 such gear.

The movement of the clutch element 32 is effected and controlled by shifting rods 36, Fig. 3, the free ends of which engage with the yoke or groove 35, while their opposite ends are secured in iron blocks 37 fitted to slide in receptacles formed by the pole pieces of the dynamo, and covers 38, as shown in Fig. 5.

In Fig. 3 the above described elements are 55 shown in their normal position, but assuming the field magnet of the dynamo-motor to be strongly energized, its frame or pole pieces will tend to draw the blocks 37 toward the gear wheels. The attraction of the 60 blocks 37 toward the pole pieces of the field magnets is due not only to the increase in the flux in the magnetic field, but is also due to a change of polarity of certain of the pole pieces, which will be described later, resulting in a re-arrangement of the magnetic

circuit in such a manner as to aid very materially in the attraction of the said blocks 37. This will move the gear wheel 34 and clutch 32 to the right against the force of a spiral spring 39, and bring the gear 34 and 70 pinion 25 and pinion 33 and gear 27 into mesh. These parts are returned to normal position by spring 39 as soon as the circuit in the dynamo motor is interrupted.

The result of the meshing of the gears 75 above set forth is as follows: When the circuit to the dynamo motor is closed, the latter will slowly rotate and shift the clutch to the right to establish the gearing connection described. The cranking operation of the 80 engine will thus be effected and the shaft 24 will be turned in an anticlockwise direction. The rollers 28 of the clutch 26 traveling to the wide portion of the notches will now slip, but the clutch 32 will bind, and power 85 will then be transmitted through the pinion 25, the gear wheel 34, the pinion 33, the gear wheel 27 and the projection 30 to the timing gears of the engine. As soon as the engine becomes self-actuated, its speed will 90 greatly increase, which will result in the projection 30 being driven by the engine instead of by the dynamo-motor, whereupon the gear 27 will be rotated in a counter-clockwise direction, which will result in locking 95 the clutch 26 and causing a direct drive of the shaft 24. At the same time, the pinion 33 will be rotated by the gear 27 in a clockwise direction, whereby the rollers of clutch 32 will be caused to slip, thus preventing any 100 ill effect due to the difference in speed between the two gear wheels 27 and 34.

In Figs. 6 and 7 is illustrated the preferred construction of the frame or polar structure of the dynamo motor. The field 105 cores are composed of groups of laminæ 40 and 41 bolted together and then united, as illustrated.

The circuit connections and mode of operation of the invention are illustrated in Fig. 110 1. In this figure the rod 5, which, as above described, may be moved either by a pedal or by a lever, is shown as provided with a double cam 43 in addition to the cam 6 of Fig. 12. When this rod is forced to the left 115 for starting the engine, the insulated stud 44, which normally rests upon the lowest step of the cam 43 is forced by the second step to lower the contact 45 to which it is attached into engagement with a contact 120 terminal 46 beneath it. The normal or inoperative condition of the circuits and other elements is as represented in the figure, but the operation of the rod 5 above described, brings about the closing of what may be 125 termed the initial cranking circuit, this movement not being sufficient to cause cam 6 to raise the brushes 20, nor to lower the brushes 14 and 16 into contact with their commutator. The circuit connections estab- 130

lished by the initial movement of the rod 5 may be thus specifically traced. From the battery 47 through wires 48 and 49 to and through contacts 45 and 46 at which point 5 the circuit divides, a portion of the current flowing through wire 50 to one of the two 10 dynamo windings 51, thence through wire 52 to the other half of the same winding, then by wire 53 to the lower terminal 54 of 15 a voltage regulator through the resistance coil 55, which is on the plunger element of 20 the regulator, to the the ground or framework of the machine to which the opposite 25 terminal of the battery is connected.

15 The other branch of the circuit thus formed is from the contact 46 across to a contact 56 engaging therewith, wires 57 and 58, across the two brushes 20, the commutator, and back to the battery through the 20 ground or frame of the machine. These two circuits thus formed, one through the fine 25 wire field coils 51 and the other through the two brushes 20 will operate the dynamo very slowly as a motor to permit the meshing 30 of the various gears.

A further movement of the rod 5 causes another step of the cam 43 to engage the stop 44 and moves the latter to a position in which it breaks the contact between terminals 56 and 46 and at the same time brings the cam 6 into operation to lower the four 35 motor brushes and raise the two generator brushes, whereupon the dynamo would operate as a motor with a strong torque by the establishment of the following circuits: from the battery 47, through conductor 48 to the point 59, where the path branches, one part leading through field coils 60 to the 40 motor brush 16, from which the current divides to the two motor brushes 13 and 15 and thence to the frame of the machine back to the battery. The other branch is to motor field coil 61 to the brush 14 and thence to brushes 13 and 15 and back to the battery. 45 Another path for current will at the same time be formed as follows: from the battery, through wires 48 and 49, across the contacts 45 and 46, wire 50, the two fine wire coils 51 of the dynamo to and through the resistance 50 coil 55 to the frame of the machine and back to the battery.

As a result of the completion of these circuits, the dynamo will be converted into a four pole motor of heavy torque with a field 55 magnet energized by both the coarse wire coils 60 and 61 and the fine wire coils 51, and will operate with a field of sufficient strength to fully actuate the gear shifting mechanism 36 and 37 of Figs. 4 and 5 and 60 start the motor in operation.

As soon as this operation has been effected and the engine is running, the rod 5 is permitted, by the operation of a pedal or lever, to return to its normal position to re- 65 establish the circuit conditions shown in

Fig. 1 and to lift the motor brushes and lower those of the generator. This is technically known as the generating or off position, and will result in the establishment of the following circuits: Starting from the 70 generator brush 20 on the right, the path of current is through wires 58 and 57, across the contacts 56 and 46, wire 50, generator fields 51, wire 53, resistance coil 55, and to the frame of the machine back to the opposite generator brush. This circuit is in reality the shunt circuit of the generator which, as appears from the above description, includes the governor or regulating resistance unit 55 of the voltage regulator. 75 80

The charging circuit is as follows: from the right hand generator brush 20 through wire 58, wire 62, to the point 63, where the circuit will branch, one path being through wire 64 to the coil 65 of the voltage regulator, through wire 66 and the rheostat coil 67 to the frame of the machine, and the other path from point 63, the fine wire coil of the cut-out relay 68 to the frame of the machine. The current passing through this 90 coil 68 will attract the armature 69, closing contacts 70, which will then permit the current to flow directly from 63 to and through the coarse-wire coil 71 and through the contacts 70, the wire 72, and wire 48 to the battery and back through the frame of the machine to the left hand brush. 95

In view of the above further description of operation is hardly necessary. The circuit being closed, the pedal or lever operating the rod 5 is shifted to start the engine. This results in first directing the current through the generator brushes and the fine wire coils of the generator and slowly revolving the gears. As soon as the latter are 100 caused to engage, the generator brushes, by the further movement of the rod 5 are lifted and the motor brushes lowered into engagement with the commutator. The engine is thus started by a motor of high torque, and 105 as soon as it becomes self-propelling the rod 5 is drawn back, which lifts the motor brushes and lowers those of the generator which thereupon charges the battery, under the control of the voltage regulator and cut out 110 relay, which devices are common in arrangements of this kind. 115

From the foregoing description it will be noted that the circuit connections are such that all field pieces are active, whether the machine is operating as a motor or as a generator. By "active" is understood to mean that the lines of magnetic force emanate from or enter the pole pieces whenever the field is energized during the operation of the machine. When operating as a motor, the pole pieces of the machine will be alternately positive and negative, taken in order around the armature. Thus the status of the machine will be that of a multi-polar machine. 120 125 130

When the machine operates as a generator, the change of field connections is such as to produce a change of polarity of certain of the pole pieces, causing for example, in the 5 machine illustrated, the pole pieces on one side of a plane passing through the armature perpendicular to the axes of the field windings, to be positive and on the other side, to be negative. The status of the 10 machine is then that of a bi-polar machine, since the effect is practically the same as if the pole pieces of like sign were combined in one piece.

In other words, the effect of the field upon 15 the armature of the dynamo electric machine is multi-polar under one set of conditions, and bi-polar under other conditions.

In the foregoing description, the electric machine has been referred to as a motor 20 generator, a dynamo motor or as a dynamo electric machine; and it should be understood that any of these terms refer to the machine which forms a part of the starting system.

25 While the form of mechanism herein shown and described constitutes a preferred form of embodiment of the invention, it is to be understood that other forms might be adopted, all coming within the scope of the 30 claims which follow.

What I claim is:

1. In a dynamo electric machine, the combination with an armature having a motor winding and a generator winding each connected with a separate commutator; of a plurality of pole pieces; means for changing the polarity of certain pole pieces and for bringing the motor armature winding or the generator armature winding into operation 35 in order to change the status of the machine to a multi-polar motor or a bi-polar generator, but permitting the number of active pole pieces to remain the same.

2. In a dynamo electric machine, the combination with an armature having a motor winding and a generator winding each winding connected with a commutator; of a field comprising a plurality of pole pieces, a motor field winding which when energized will 40 produce a multipolar effect, and a generator field winding which when energized will produce a bi-polar effect, all of the pole pieces being made active by either winding; and means for selecting one of the armature 45 windings and for changing the field connections in order to effect a change of status of the machine to a multi-polar motor or a bi-polar generator.

3. In a dynamo electric machine, the combination with an armature having a motor winding and a generator winding each connected with a separate commutator and brushes coöperating therewith; of a field comprising a plurality of pole pieces, and 55 a motor field winding which when energized

will produce a multi-polar effect; and a generator field winding which when energized will produce a bi-polar effect; and means for shifting certain of the brushes out of operative position while permitting other 70 brushes to remain in operation, and for changing the field connections, to change the status of the machine either to a multi-polar motor or to a bi-polar generator.

4. In a dynamo electric machine, the combination with an armature having a motor winding and a generator winding each connected with a commutator having a set of brushes coöperating therewith; of a field comprising a plurality of pole pieces and a field 80 circuit; a means for shifting the sets of brushes into and out of contact with their respective commutators and for changing the field connections to change the status of the machine either to a multi-polar motor 85 or to a bi-polar generator.

5. In a dynamo electric machine, the combination with an armature having a motor winding and a generator winding each connected with a commutator having a set of 90 brushes coöperating therewith; of a field comprising a plurality of pole pieces, and a motor field winding which when energized will produce a multi-polar effect, and a generator field winding which when energized 95 will produce a bi-polar effect, all of the pole pieces being made active by either winding; and a movable member operating by shifting the sets of brushes into and out of contact with their respective commutators, and 100 by changing the field connections, to change the status of the machine either to a multi-polar motor or a bi-polar generator.

6. In a dynamo electric machine, the combination with an armature having motor and generator windings connected with commutators; two generator brushes; a number of motor brushes greater than two; and two sets of field windings; circuit connections between the field windings and the brushes; a movable member, and means thereon for shifting the circuit connections and at the same time moving the several brushes, whereby the motor brushes may be maintained in contact with the motor commutator 105 and both sets of field windings in circuit, or the two generator brushes maintained in contact with the generator commutator and one of the sets of field windings in circuit. 110

7. In an engine starting system, the combination with an engine and a storage battery; of a dynamo motor having both motor and generator brushes and adapted to start the engine and charge the battery when the engine is running, means for lifting the motor or the generator brushes, circuit connections for both motor and generator, circuit controlling means in said circuits, and a member operably connected with the brush lifting means and the circuit controlling de- 115 120 125 130

vices by the movement of which the brushes are controlled and the proper circuit connections effected.

8. In an engine starting system, the combination with an engine, of a starting device therefor, including a motor-generator having a plurality of field and armature windings and pole pieces; mechanical connections between the motor-generator and the engine, whereby the motor-generator may be connected to the engine to operate at one ratio of speed for starting purposes, and at a different ratio of speed for generating purposes; and an operating member operable to select certain of the field and armature windings, and the mechanical connections for giving the high speed ratio for starting purposes, and to select other of the armature windings and a different arrangement of the field windings resulting in the reversal of polarity of certain of the pole pieces, and different mechanical connections between the motor generator and engine when the engine is driving the motor generator as a generator.

9. In a dynamo electric machine, the combination with a field magnet; of an armature having a motor winding and a generator winding each connected with a commutator; a set of motor brushes; a set of generator brushes; a revoluble ring having provisions thereon for lifting either set of brushes while lowering the other according to its position; and a movable member for turning said ring.

35 10. In a dynamo electric machine, the combination with a field magnet, of an armature having motor and generator windings, each connected to a commutator; a set of motor commutator brushes; a set of generator brushes; a mechanical element normally positioned so as to positively maintain certain of the motor brushes in inoperative position while permitting the generator brushes to be in operative position; provisions associated with said certain motor brushes, for causing the remaining motor brushes also to be maintained in inoperative position when said mechanical element is in normal position; and an operating member for shifting the mechanical element from its normal position, to effect the shifting of the generator brushes out of operative position and to permit the motor brushes to move into operative position.

55 11. In an engine starting system, the combination with an engine; of a starting device therefor, including a motor generator having a plurality of field windings and pole pieces; mechanical connections between the motor generator and engine, whereby the motor-generator may be connected to the engine to operate at one ratio of speed for starting purposes, and at a different ratio of speed for generating purposes; means for changing the polarity of certain of the pole

pieces; and means rendered effective by the change of polarity for coupling up one of the mechanical connections.

12. In an engine starting system, the combination with an engine; of a starting device therefor, including a motor generator having a magnetic field the lines of flux of which are arranged normally in a certain manner; mechanical connections between the motor-generator and engine, whereby the motor-generator may be connected to the engine to operate at one ratio of speed for starting purposes, and at a different ratio of speed for generating purposes; means for effecting a rearrangement of the lines of flux of the magnetic field; and means magnetically operated by said field upon said rearrangement of flux for coupling up certain of the mechanical connections.

13. In an engine starting system, the combination with an engine; of a starting device therefor including a motor-generator having a plurality of pole pieces; gearing between the engine and motor-generator; a storage battery; and circuit connections between the battery and motor-generator including a circuit making device movable into normal position to effect the slow initial movement of the motor-generator as a two pole motor, said device being movable into another position to effect a change of status of the motor-generator to a high torque multi-polar motor for the main engine starting operation, and said device being movable to normal position, after the engine has become self-actuating, to restore the status of the motor-generator to "bi-polar" for generating purposes.

14. In an engine starting system, the combination with an engine; of a starting device therefor including a motor-generator having a plurality of pole pieces; mechanical connections between the motor-generator and the engine; a storage battery; circuit connections between the battery and the motor-generator including a circuit making device movable into normal position to effect the slow initial movement of the motor-generator as a two-pole motor, said device being movable into another position to effect a change of status of the motor-generator to a high torque multi-polar motor, and said device being movable after the engine has become self-actuating, to normal position to restore the status of the motor-generator to "bi-polar" for generating purposes; and means rendered effective upon the change of status to a multi-polar motor for coupling up certain of the mechanical connections.

15. In an engine starting system, the combination with an engine, of a starting device therefor, including a motor-generator having a plurality of field and armature circuits and pole pieces; mechanical connections between the engine and motor-genera-

- tor; a storage battery; and circuit connections between the battery and motor-generator including a circuit making device movable into normal position to select certain of the 5 field and armature circuits to effect the slow initial movement of the motor-generator as a two pole motor, said device being movable into another position to select other armature and field circuits to effect a change of 10 status of the motor-generator to a high torque multi-polar motor for the main engine starting operation, and said device, being movable after the engine has become self-actuating, to normal position to restore 15 the status of the motor-generator to "bi-polar" for generating purposes.
16. In an engine starting system, the combination with an engine, of a starting device therefor, including a motor-generator having 20 a plurality of field and armature circuits and pole pieces; mechanical connections between the engine and motor-generator; a storage battery; circuit connections between the battery and motor-generator including 25 a circuit making device movable into normal

position to select certain of the field and armature circuits to effect the slow initial movement of the motor-generator as a two pole motor, said device being movable into another position to select other armature 30 and field circuits to effect a change of status of the motor-generator to a high torque multi-polar motor for the main engine starting operation, and said device, being movable, after the engine has become self-actuating, to normal position to restore the status of the motor-generator to "bi-polar" for generating purposes; and means rendered effective upon the change of status to a multi-polar motor for coupling up certain of the 35 mechanical connections.

In testimony whereof we affix our signatures in the presence of two subscribing witnesses.
